UNITED STATES PATENT OFFICE.

JOHN J. COCHRAN, OF SAN FRANCISCO, CALIFORNIA.

HANGER FOR CURTAINS.

SPECIFICATION forming part of Letters Patent No. 786,729, dated April 4, 1905.

Application filed July 8, 1904. Serial No. 215,813.

To all whom it may concern:

Be it known that I, JOHN J. COCHRAN, a citizen of the United States, residing at San Francisco, in the county of San Francisco and State 5 of California, have invented new and useful Improvements in Hangers for Curtains, of which the following is a specification.

This invention relates to hangers for curtains.

10 The objects of the invention are to improve and simplify the construction of such devices.

With these and other objects in view, which will appear as the description proceeds, the invention resides in the novel combination 15 and arrangement of parts and in the details of construction hereinafter described and claimed as a practical embodiment of the invention.

20 Referring to the accompanying drawings, forming part of this specification, Figure 1 is a perspective view showing the upper portion of the window-frame with two devices, constructed in accordance with the invention, applied thereto. Fig. 2 is a plan view of the 25 device, the double curtain-rod being broken away. Fig. 3 is a detail perspective of one of the brackets for holding the operating-rod in position. Fig. 4 is a similar view of one 30 of the clips for holding the double curtain-rod in proximity to the window.

Like reference-numerals indicate corresponding parts in the different figures.

As above indicated, two of the improved curtain-hangers are illustrated in Fig. 1. It 35 will be understood, however, that the construction of both devices is identical and that the description of one will convey an understanding of the other. Furthermore, it will be understood that although the invention is 40 illustrated in connection with a window, its use is not to be limited in this respect, as it is adapted to be applied with equal facility to doors or other places wherein it is desirable to use curtains.

45 The numeral 1 indicates the frame of a window. Attached in any suitable manner to the frame 1 is a plurality of brackets 2. As illustrated in the drawings, the brackets are preferably attached to the frame by means of 50 screws or nails, one of such brackets being

disposed at the upper portion of the frame and the other adjacent to the meeting ends of the upper and lower sashes, so as to be within convenient reach of a person standing upon the floor close to the window. Journaled in 55 the brackets 2 is an operating-rod 3, upon the lower portion of which is mounted a sleeve 4, provided with a transversely-extending handle 5. The sleeve 4 is longitudinally adjustable upon the rod 3 by means of an adjusting-screw 6, in order that the rod may be adjusted 60 easily to windows of varying heights. Upon the upper end of the rod 3 is mounted a socket-piece 7, which, like the sleeve 4, is longitudinally adjustable upon said rod by means 65 of an adjusting-screw 8. The socket-piece 7 is formed with two tubular extensions 9 9, each of which is longitudinally bored or formed with a socket to receive one end of a curtain-rod, the ends 10 10 of which are bent 70 into parallel relation with each other to form a double curtain-rod. The double curtain-rod is adapted to be removed easily from the socket-piece 7 by loosening the screws 11. It 75 will be seen that when the curtain-rod is removed from the socket-piece the curtain-rings or other supporting devices for the curtain may be engaged therewith without difficulty, after which the curtain-rod may be reengaged with the socket-piece and held securely thereon by tightening the screws 11.

By reason of the fact that the rod 3 is journaled in the brackets 2 said rod may be rotated, by means of the handle 5, to swing the curtain-rod, with its supported curtain, away 85 from the window in order to permit such window to be cleaned or in order to avoid obstructing the passage of light therethrough. A spring-clip, such as 12, is fastened upon the window-frame in any suitable manner, 90 such as by screws or nails, in order normally to maintain the curtain in its proper position with respect to the window.

The weight of the operating-rod 3 is supported upon the sleeve 4 and lower bracket 95 2, and therefore serves normally to prevent the rod from losing its engagement with the journal-brackets in which it is mounted. When it is desired to remove the curtain and hanger from the window, the rod 3 is raised 100

- slightly until its lower end leaves the lower bracket 2, after which it is possible to move said rod out of alignment with said lower bracket and by lowering it to cause its disengagement from the upper bracket. In this manner the entire curtain and hanger may be removed, leaving upon the window-frame only the brackets 2 and clip 12. It will be observed, moreover, that as the lower end of the rod 3 is within convenient reach of a person standing upon the floor near the window the employment of a step-ladder or other similar device for taking down or hanging the curtains is unnecessary.
- 15 As before indicated, the longitudinal adjustment of the sleeve 4 and socket-piece 7 upon the rod 3 enables the device to be applied readily to windows or doors of varying sizes.
- 20 Having thus fully described the invention, what is claimed as new is—
1. A curtain-hanger comprising a rotary operating-rod, a socket-piece carried thereby, and a curtain-rod having its ends bent into

parallel relation with each other and fitted into the socket-piece. 25

2. A curtain-hanger comprising a rotary operating-rod, a sleeve longitudinally adjustable thereon, a handle on the sleeve, a socket-piece longitudinally adjustable upon the operating-rod, and a curtain-rod removably connected with the socket-piece. 30

3. The combination of a frame, a plurality of brackets carried thereby, a clip connected therewith, a rotary operating-rod journaled in the brackets, a longitudinally-adjustable sleeve upon the operating-rod, a longitudinally-adjustable socket-piece upon the operating-rod, and a curtain-rod having its opposite ends bent into parallel relation with each other and removably fitted into the socket-piece. 35 40

In testimony whereof I affix my signature in presence of two witnesses.

JOHN J. COCHRAN.
